**OXIDATIVE DEHYDROGENATION OF NON-
AROMATIC CYCLIC HYDROCARBON HAV-
ING AT LEAST ONE UNSATURATED BOND
IN SIDE CHAIN**

ABSTRACT OF THE DISCLOSURE

Method for the oxidative dehydrogenation of a non-aromatic cyclic hydrocarbon having at least one unsaturated bond in a side chain which comprises contacting the non-aromatic cyclic hydrocarbon in the presence of oxygen with a catalyst consisting essentially of palladium oxyhydrate to give the corresponding aromatic hydrocarbon retaining the said unsaturated bond.

The present invention relates to a method for the oxidative dehydrogenation of a non-aromatic cyclic hydrocarbon having at least one unsaturated bond in a side chain.

Hitherto, it has been known that the dehydrogenation of a non-aromatic cyclic hydrocarbon to the corresponding aromatic hydrocarbon can be accomplished by contacting the non-aromatic cyclic hydrocarbon with palladium metal, platinum metal, nickel metal or chromium oxide in the absence of oxygen at an elevated temperature. When the non-aromatic cyclic hydrocarbon has a side chain including an unsaturated bond, however, the unsaturated bond is hydrogenated in such process. For instance, 4-vinylcyclohexene-1 is dehydrogenated at 400° C. in the presence of chromium oxide to give as the main product ethylbenzene [Chemical Abstracts, vol. 34, col. 5418 (1940)]. Further, for instance, the dehydrogenation of 4-vinylcyclohexene-1 at 290 to 300° C. in the presence of palladium metal yields solely ethylbenzene [Chemical Abstracts, vol. 33, col. 3329 (1939)]. Even when the dehydrogenation in the latter case is effected at a lower temperature, i.e. 135 to 150° C., there proceeds a disproportionation reaction to afford a mixture of ethylbenzene and ethylcyclohexane as shown in the following formulae:

Thus, the dehydrogenation of a non-aromatic cyclic hydrocarbon having an unsaturated bond in a side chain to the corresponding aromatic hydrocarbon retaining the unsaturated bond in an appreciable conversion rate and selectivity has never been achieved.

In the course of the study seeking a method which can dehydrogenate a non-aromatic cyclic hydrocarbon having an unsaturated bond in a side chain selectively to the corresponding aromatic hydrocarbon retaining the unsaturated bond, the present inventors had found that a platinum group metal (e.g. palladium, platinum, rhodium, iridium, ruthenium, osmium) realizes such selective dehydrogenation when used in the presence of oxygen. Since

the conversion rate is, however, considerably low, the said metal is not applicable to the industrial dehydrogenation.

As the result of the subsequent study, there has now been found that, when palladium oxyhydrate is used as a catalyst in the presence of oxygen, a non-aromatic cyclic hydrocarbon having an unsaturated bond in a side chain is dehydrogenated in a high conversion rate with an excellent selectivity to the corresponding aromatic hydrocarbon retaining the unsaturated bond.

10 Accordingly, a basic object of the present invention is to embody a method for the oxidative dehydrogenation of a non-aromatic cyclic hydrocarbon having at least one unsaturated bond in a side chain to the corresponding aromatic hydrocarbon retaining the unsaturated bond in a single step. Another object of this invention is to embody a process for the preparation of an aromatic hydrocarbon having an unsaturated bond in a side chain selectively from the corresponding non-aromatic cyclic hydrocarbon having an unsaturated bond in a side chain in a single step. A further object of the invention is to embody a catalyst which can dehydrogenate in the presence of oxygen a non-aromatic cyclic hydrocarbon having at least one unsaturated bond in a side chain to the corresponding aromatic hydrocarbon retaining the unsaturated bond in a high conversion rate with an excellent selectivity. These and other objects will be apparent to those conversant with the art to which the present invention pertains from the foregoing and subsequent descriptions.

According to the present invention, a non-aromatic cyclic hydrocarbon having at least one unsaturated bond in a side chain is contacted with a catalyst consisting essentially of palladium oxyhydrate in the presence of oxygen to give the corresponding aromatic hydrocarbon retaining the unsaturated bond as unchanged.

The non-aromatic cyclic hydrocarbon is monocyclic or polycyclic and has one or more side chains, of which at least one bears at least one unsaturated bond. Specifically, there are exemplified hydrocarbons represented by either one of the following formulae:

45 wherein X is a substituted or unsubstituted monocyclic or bicyclic non-aromatic hydrocarbon group such as cyclohexyl, lower alkylcyclohexyl (e.g. 2-methylcyclohexyl, 2-ethylcyclohexyl), di(lower)alkylcyclohexyl (e.g. 2,4-dimethylcyclohexyl, 2-methyl-4-ethylcyclohexyl), tri(lower)alkylcyclohexyl (e.g. 2,4,6-trimethylcyclohexyl, 2,4-dimethyl-6-ethylcyclohexyl), 55 cyclohexenyl, lower alkylcyclohexenyl (e.g. 2-methylcyclohexen-1-yl, 3-ethylcyclohexen-1-yl), di(lower)alkylcyclohexenyl (e.g. 2,4-dimethylcyclohexen-1-yl), 60 2-methyl-4-ethylcyclohexen-1-yl), tri(lower)alkylcyclohexenyl (e.g. 2,4,6-trimethylcyclohexen-1-yl, 2,6-dimethyl-4-ethylcyclohexen-1-yl), cyclohexadienyl, 65 lower alkylcyclohexadienyl (e.g. 2-methylcyclohexadien-1,3-yl, 2-ethylcyclohexadien-1,3-yl), di(lower)alkylcyclohexadienyl (e.g. 2,4-dimethylcyclohexadien-1,3-yl, 70 2,4-diethylcyclohexadien-1,3-yl), tri(lower)alkylcyclohexadienyl (e.g. 2,4,6-trimethylcyclohexadien-1,3-yl),

2,4,6-triethylcyclohexadien-1,3-yl),
 perhydronaphthyl,
 lower alkylperhydronaphthyl (e.g. 2-methylperhydro-
 naphthyl,
 3-methylperhydronaphthyl),
 di(lower)alkylperhydronaphthyl (e.g. 2,4-dimethylperhy-
 dronaphthyl,
 2-methyl-4-ethylperhydronaphthyl),
 tri(lower)alkylperhydronaphthyl (e.g. 2,4,6-trimethyl-
 perhydronaphthyl,
 2,4,6-triethylperhydronaphthyl),
 tetrahydronaphthyl,
 lower alkyltetrahydronaphthyl (e.g. 2-methyl-1,2,3,4-
 tetrahydronaphthyl,
 4-methyl-1,2,3,4-tetrahydronaphthyl),
 di(lower)alkyltetrahydronaphthyl (e.g. 2,4-dimethyl-
 1,2,3,4-tetrahydronaphthyl,
 2,4-diethyl-1,2,3,4-tetrahydronaphthyl),
 tri(lower)alkyltetrahydronaphthyl (e.g. 2,4,6-trimethyl-
 1,2,3,4-tetrahydronaphthyl,
 2,4-dimethyl-3-ethyl-1,2,3,4-tetrahydronaphthyl),
 1,2,3,4-tetrahydronaphthyl),
 dihydronaphthyl,
 lower alkylidihydronaphthyl (e.g. 2-methyl-1,2-dihydro-
 naphthyl,
 2-methyl-3,4-dihydronaphthyl),
 di(lower)alkylidihydronaphthyl (e.g. 2,4-dimethyl-1,2-di-
 hydronaphthyl,
 2,4-dimethyl-3,4-dihydronaphthyl) or tri(lower)alkylid-
 hydronaphthyl (e.g. 2,4,6-trimethyl-1,2-dihydronaphth-
 yl,
 2,3-dimethyl-6-ethyl-1,2-dihydronaphthyl),
 Y is a lower alkylene group (e.g. methylene,
 ethylene,
 propylene,
 trimethylene,
 tetramethylene,
 pentamethylene),
 R₁, R₂ and R₃ are each a hydrogen atom,
 a lower alkyl group (e.g. methyl,
 ethyl,
 propyl,
 isopropyl,
 butyl),
 a cyclohexyl group, a lower alkylcyclohexyl group (e.g.
 2-methylcyclohexyl,
 2-ethylcyclohexyl),
 a di(lower)alkylcyclohexyl group (e.g. 2,4-dimethylcyclo-
 hexyl,
 2-methyl-4-ethylcyclohexyl),
 a tri(lower)alkylcyclohexyl group (e.g. 2,4,6-trimethyl-
 cyclohexyl,
 2,4-dimethyl-6-ethylcyclohexyl),
 a cyclohexyl(lower)alkyl group (e.g. cyclohexylmethyl,
 2-cyclohexylethyl),
 a lower alkylcyclohexyl(lower)alkyl group (e.g. 4-meth-
 ylcyclohexylmethyl,
 2-(4-methylcyclohexyl)ethyl),
 a di(lower)alkylcyclohexyl(lower)alkyl group (e.g. 2,4-
 dimethylcyclohexylmethyl,
 2-(2,4-dimethylcyclohexyl)ethyl),
 a tri(lower)alkylcyclohexyl(lower)alkyl group (e.g. 2,4-
 6-trimethylcyclohexylmethyl,
 2,6-dimethyl-4-ethylcyclohexylmethyl),
 a cyclohexenyl group,
 a lower alkylcyclohexenyl group (e.g. 2-methylcyclo-
 hexen-1-yl,
 3-ethylcyclohexen-1-yl),
 a di(lower)alkylcyclohexenyl group (e.g. 2,4-dimethyl-
 cyclohexen-1-yl,
 2-methyl-4-ethylcyclohexen-1-yl),
 a tri(lower)alkylcyclohexenyl group (e.g. 2,4,6-trimeth-
 ylcyclohexen-1-yl,
 2,6-dimethyl-4-ethylcyclohexen-1-yl),

a cyclohexenyl(lower)alkyl group (e.g. cyclohexen-1-yl-
 methyl,
 2-cyclohexen-1-ylethyl),
 a lower alkylcyclohexenyl(lower)alkyl group (e.g. 4-
 methylcyclohexen-1-ylmethyl,
 5 2-(4-methylcyclohexen-1-yl)-ethyl),
 a di(lower)alkylcyclohexenyl(lower)alkyl group (e.g.
 2,4-dimethylcyclohexen-1-ylmethyl,
 2-(2,4-dimethylcyclohexen-1-yl)ethyl),
 10 a tri(lower)alkylcyclohexenyl(lower)alkyl group (e.g.
 2,4,6-trimethylcyclohexen-1-ylmethyl,
 2,6-dimethyl-4-ethylcyclohexen-1-ylmethyl),
 a cyclohexadienyl group,
 a lower alkylcyclohexadienyl group (e.g. 2-methylcyclo-
 hexadien-1-yl, 2-ethylcyclohexadien-1-yl),
 15 a di(lower)alkylcyclohexadienyl group (e.g. 2,4-di-
 methylcyclohexadien-1-yl,
 2,4-diethylcyclohexadien-1-yl),
 a tri(lower)alkylcyclohexadienyl group (e.g. 2,4,6-tri-
 ethylcyclohexadien-1-yl),
 20 2,4,6-triethylcyclohexadien-1-yl),
 a cyclohexadienyl(lower)alkyl group (e.g. cyclohexadien-
 1-ylmethyl,
 2-cyclohexadien-1-yl-ethyl),
 25 a lower alkylcyclohexadienyl(lower)alkyl group (e.g. 2-
 methylcyclohexadien-1,3-ylmethyl,
 2-(4-methylcyclohexadien-1,3-yl)-ethyl),
 a di(lower)alkylcyclohexadienyl(lower)alkyl group (e.g.
 2,4-dimethylcyclohexadien-1,3-ylmethyl,
 30 2-(2,4-dimethylcyclohexadien-1,3-yl)ethyl),
 a tri(lower)alkylcyclohexadienyl(lower)alkyl group (e.g.
 2,4,6-trimethylcyclohexadien-1,3-ylmethyl,
 2-(2,4,6-trimethylcyclohexadien-1,3-yl)-ethyl),
 an aryl group (e.g. phenyl),
 35 tolyl,
 xylyl,
 naphthyl)
 or an ar(lower)alkyl group (e.g. benzyl, phenethyl)
 40 and m is an integer from 1 to 3. More specifically, there
 are exemplified the following hydrocarbons:
 lower alkenylcyclohexane (e.g. vinylcyclohexane,
 propenylcyclohexane,
 isopropenylcyclohexane,
 45 allylcyclohexane),
 lower alkyl-lower alkenylcyclohexane (e.g. 1-methyl-2-
 vinylcyclohexane,
 1-methyl-3-vinylcyclohexane,
 1-ethyl-3-vinylcyclohexane,
 50 1-methyl-2-propenylcyclohexane,
 1-ethyl-3-isopropenylcyclohexane,
 1-methyl-4-allylcyclohexane,
 1-ethyl-2-allylcyclohexane,)
 di(lower)alkyl-lower alkenylcyclohexane (e.g. 1,2-di-
 methyl-3-vinylcyclohexane,
 55 1,3-dimethyl-4-vinylcyclohexane,
 1,2-diethyl-3-vinylcyclohexane,
 1,2-dimethyl-3-propenylcyclohexane,
 1,4-dimethyl-2-isopropenylcyclohexane,
 1,2-dimethyl-3-allylcyclohexane,
 60 1-methyl-2-ethyl-4-allylcyclohexane),
 tri(lower)alkyl-lower alkenylcyclohexane (e.g. 1,2,3-tri-
 methyl-4-vinylcyclohexane,
 1,2-dimethyl-3-ethyl-4-isopropenylcyclohexane),
 65 di(lower)alkenylcyclohexane (e.g. 1,2-divinylcyclohex-
 ane,
 1,3-divinylcyclohexane,
 1,2-dipropenylcyclohexane,
 1,4-diisopropenylcyclohexane,
 1,3-diallylcyclohexane),
 70 lower alkyl-di(lower)alkenylcyclohexane (e.g. 1-methyl-
 2,3-divinylcyclohexane,
 1-methyl-2,5-divinylcyclohexane,
 1-ethyl-2,4-divinylcyclohexane,
 75 1-methyl-2,4-dipropenylcyclohexane,

1-methyl-2,3-diisopropenylcyclohexane,
 1-ethyl-2,4-disopropenylcyclohexane,
 1-methyl-3,5-diallylcyclohexane),
 di(lower)alkyl-di(lower)alkenylcyclohexane (e.g. 1,2-di-
 methyl-3,4-divinylcyclohexane,
 1,2-diethyl-3,4-divinylcyclohexane,
 1,3-dimethyl-2,5-dipropenylcyclohexane,
 1,3-dimethyl-2,5-diisopropenylcyclohexane,
 1,2-dimethyl-3-vinyl-5-allylcyclohexane),
 tri(lower)alkyl-di(lower)alkenylcyclohexane (e.g. 1,3,5-
 trimethyl-2,6-divinylcyclohexane,
 1,3-dimethyl-2-ethyl-4-vinyl-6-allylcyclohexane,
 tri(lower)alkenylcyclohexane (e.g. 1,3,5-trivinylcyclo-
 hexane,
 1,3-divinyl-5-allylcyclohexane),
 lower alkyl-tri(lower)alkenylcyclohexane (e.g. 1-methyl-
 2,4,6-trivinylcyclohexane,
 1-ethyl-2,4,6-triallylcyclohexane),
 di(lower)alkyl-tri(lower)alkenylcyclohexane (e.g. 1,3-di-
 methyl-2,4,6-trivinylcyclohexane,
 1,3-diethyl-2,4,6-triallylcyclohexane),
 tri(lower)alkyl-tri(lower)alkenylcyclohexane (e.g. 1,3,5-
 trimethyl-2,4,6-trivinylcyclohexane,
 1,3-dimethyl-5-ethyl-2,4,6-trivinylcyclohexane),
 dicyclohexyl(lower)alkene (e.g. 1,2-dicyclohexylethylene, 25
 1-cyclohexyl-2-cyclohexylmethylethylene),
 cyclohexyl-lower alkylcyclohexyl(lower)alkene (e.g.
 1-cyclohexyl-2-(4-methylcyclohexyl)ethylene,
 1-cyclohexyl-2-(4-ethylcyclohexylmethyl)ethylene),
 cyclohexyl-di(lower)alkylcyclohexyl(lower)alkene (e.g.
 1-cyclohexyl-2-(2,4-dimethylcyclohexyl)ethylene,
 1-cyclohexyl-2-(2-methyl-4-ethylcyclohexylmethyl)
 ethylene),
 lower alkylcyclohexyl-lower alkylcyclohexyl(lower)
 alkene (e.g. 1-(4-methylcyclohexyl)-2-(4-methyl-
 cyclohexyl)ethylene,
 1-(2-methylcyclohexyl)-2-(4-methylcyclohexylmethyl)
 ethylene),
 lower alkylcyclohexyl-di(lower)alkylcyclohexyl(lower)
 alkene (e.g. 1-(4-methylcyclohexyl)-2-(2,4-dimethyl-
 cyclohexyl)ethylene,
 1-(2-ethylcyclohexyl)-2-(2-methyl-4-ethylcyclohexyl)
 ethylene),
 lower alkylcyclohexyl-tri(lower)alkylcyclohexyl(lower)
 alkene (e.g. 1-(2-methylcyclohexyl)-2-(2,4,6-trimethyl-
 cyclohexyl)ethylene,
 1-(3-ethylcyclohexyl)-2-(2,4,6-trimethylcyclohexyl-
 methyl)ethylene),
 di(lower)alkylcyclohexyl-di(lower)alkylcyclohexyl-
 (lower)alkene (e.g. 1-(2,4-dimethylcyclohexyl)-2-
 (3,5-dimethylcyclohexyl)ethylene,
 1-(2,4-dimethylcyclohexyl)-2-(2,4-dimethylcyclohexyl-
 methyl)ethylene),
 di(lower)alkylcyclohexyl-tri(lower)alkylcyclohexyl-
 (lower)alkene (e.g. 1-(2,4-dimethylcyclohexyl)-2-
 (2,4,6-trimethylcyclohexyl)ethylene,
 1-(2,4-dimethylcyclohexyl)-2-[2-(2,4,6-trimethylcyclo-
 hexyl)ethyl]ethylene),
 tri(lower)alkylcyclohexyl-tri(lower)alkylcyclohexyl-
 (lower)alkene (e.g. 1-(2,4,6-trimethylcyclohexyl)-2-
 (2,4,6-trimethylcyclohexyl)ethylene,
 1-(2,4,6-trimethylcyclohexyl)-2-[2-(2,4,6-trimethyl-
 cyclohexyl)ethyl]ethylene),
 cyclohexyl-aryl(lower)alkene (e.g. 1-cyclohexyl-2-
 phenylethylene,
 1-cyclohexyl-2-p-tolylethylene,
 1-cyclohexyl-2-benzylolethylene),
 lower alkylcyclohexyl-aryl(lower)alkene (e.g. 1-(2-
 methylcyclohexyl)-2-phenylethylene,
 1-(2-methylcyclohexyl)-2-phenethylethylene),
 di(lower)alkylcyclohexyl-aryl(lower)alkene (e.g. 1-(2-
 methylcyclohexyl)-2-phenylethylene,

dimethylcyclohexyl)-2-phenylethylene,
 1-(3,5-dimethylcyclohexyl)-2-benzylolethylene),
 tri(lower)alkylcyclohexyl-aryl(lower)alkene (e.g. 1-(2,4-
 6-trimethylcyclohexyl)-2-phenylethylene),
 5 There may be also exemplified the following hydrocar-
 bons:
 lower alkenylcyclohexene,
 lower alkyl-lower alkenylcyclohexene,
 di(lower)alkyl-lower alkenylcyclohexene,
 tri(lower)alkyl-lower alkenylcyclohexene,
 di(lower)alkenylcyclohexene,
 lower alkyl-di(lower)alkenylcyclohexene,
 di(lower)alkyl-di(lower)alkenylcyclohexene,
 tri(lower)alkylcyclohexene,

The "palladium oxyhydrate" employed as the essential component of the catalyst in the present invention is known [Gmelin-Kraut: Handbuch der anorganischen Chemie, System Nr. 65-2, p. 257; Mellor: A Comprehensive Treatise Inorganic and Theoretical Chemistry, vol. 15, p. 656] and sometimes called "palladium hydroxide" [Kirk-Othmer: Encyclopedia of Chemical Technology, vol. 10, p. 842; Lange: Handbook of Chemistry, 9th ed., p. 282, No. 1514]. The palladium oxyhydrate may be prepared, for instance, by adding an alkali (e.g. sodium hydroxide, potassium hydroxide, barium hydroxide, calcium hydroxide, magnesium hydroxide, sodium carbonate, calcium carbonate, barium carbonate, magnesium oxide, calcium oxide) to a solution of a water-soluble palladium salt (e.g. palladium chloride, palladium nitrate, palladium sulfate, potassium palladium tetrachloride) in water. As the catalyst in the present invention, palladium oxyhydrate may be used alone but is preferred to use with a suitable supporting or diluting material such as asbestos, pumice, kieselguhr, activated carbon, alumina, boria, beryllia, magneisa, titania, zirconia, silica, silica-aluminum or any other similar material. The catalyst can be used in the form of fiber, granules, mechanically formed pellets or the like.

In order to form an oxygenic atmosphere, there may be used, for instance, oxygen gas, air, a mixture of oxygen gas with an inert gas such as nitrogen, carbon dioxide or steam or a compound which can generate oxygen on heating such as hydrogen peroxide or t-butylhydroperoxide. The molar ratio of oxygen to the non-aromatic cyclic hydrocarbon is preferably from 0.1:1.0 to 10:1.0.

The oxidative dehydrogenation may be carried out over a wide range of temperature provided that it is in the range where palladium oxyhydrate used as the essential component of the catalyst can remain as such, usually at a temperature not exceeding about 600° C. (preferably from about 50 to about 350° C., more preferably from about 100 to about 300° C.), under an autogenous or a regulated pressure, ordinarily from about 0.01 to about 10 atm. (preferably from about 0.1 to about 5 atm.).

The liquid hourly space velocity, expressed by the liquid volume of the non-aromatic cyclic hydrocarbon charged per unit volume of the catalyst in unit time, may be preferably in the range of from about 0.1 to about 10 hr.⁻¹.

The method of this invention is ordinarily carried out by forming a mixture, preferably preheated, of the non-aromatic cyclic hydrocarbon to be dehydrogenated and oxygen or oxygen-containing stream and passing this mixture over the catalyst at the desired temperature. Recycle of the unconverted hydrocarbon can be employed, if desired; however, the conversion rate and selectivity are excellently high to justify a single step operation (i.e. a single pass operation). The product stream can be generally used without separation steps in a subsequent operation such as polymerization.

The product in the oxidative dehydrogenation of this invention is the aromatic hydrocarbon retaining as such an unsaturated bond in a side chain, the unsaturated bond having been present in the starting non-aromatic cyclic hydrocarbon. Such aromatic hydrocarbon includes

the one represented by either one of the following formulae:

wherein X' is a substituted or unsubstituted monocyclic or bicyclic aromatic hydrocarbon group such as phenyl, lower alkylphenyl (e.g. 2-methylphenyl, 2-ethylphenyl), di(lower)alkylphenyl (e.g. 2,4-dimethylphenyl, 2-methyl-4-ethylphenyl), tri(lower)alkylphenyl (e.g. 2,4,6-trimethylphenyl, 2,4-dimethyl-6-ethylphenyl), naphthyl, lower alkynaphthyl (e.g. 2-methylnaphthyl, 3-methylnaphthyl), di(lower)alkynaphthyl (e.g. 2,4-dimethylnaphthyl, 2-methyl-4-ethylnaphthyl) or tri(lower)alkynaphthyl (e.g. 2,4,6-trimethylnaphthyl, 2,4,6-triethylnaphthyl),

R'_1 , R'_2 and R'_3 have respectively the same significance as R_1 , R_2 and R_3 and Y and m are each as defined above. Specific examples of the aromatic hydrocarbon are as follows:

lower alkenylbenzene (e.g. styrene, propenylbenzene, isopropenylbenzene, allylbenzene), lower alkyl-lower alkenylbenzene (e.g. 1-methyl-2-vinylbenzene, 1-methyl-3-vinylbenzene, 1-ethyl-3-vinylbenzene, 1-methyl-2-propenylbenzene, 1-ethyl-3-isopropenylbenzene, 1-methyl-4-allylbenzene, 1-ethyl-2-allylbenzene), di(lower)alkyl-lower alkenylbenzene (e.g. 1,2-dimethyl-3-vinylbenzene, 1,3-dimethyl-4-vinylbenzene, 1,2-diethyl-3-vinylbenzene, 1,2-dimethyl-3-propenylbenzene, 1,4-dimethyl-2-isopropenylbenzene, 1,2-dimethyl-3-allylbenzene, 1-methyl-2-ethyl-4-allylbenzene), tri(lower)alkyl-lower alkenylbenzene (e.g. 1,2,3-trimethyl-4-vinylbenzene, 1,2-dimethyl-3-ethyl-4-isopropenylbenzene), di(lower)alkenylbenzene (e.g. 1,2-divinylbenzene, 1,3-divinylbenzene, 1,2-dipropenylbenzene, 1,4-diisopropenylbenzene, 1,3-diallylbenzene), lower alkyl-di(lower)alkenylbenzene (e.g. 1-methyl-2,3-divinylbenzene, 1-methyl-2,5-divinylbenzene, 1-ethyl-2,4-divinylbenzene, 1-methyl-2,4-dipropenylbenzene, 1-methyl-2,3-diisopropenylbenzene, 1-ethyl-2,4-diisopropenylbenzene, 1-methyl-3,5-diallylbenzene), di(lower)alkyl-di(lower)alkenylbenzene (e.g. 1,2-dimethyl-3,4-divinylbenzene, 1,2-diethyl-3,4-divinylbenzene, 1,3-dimethyl-2,5-diisopropenylbenzene, 1,2-dimethyl-3-vinyl-5-allylbenzene), tri(lower)alkyl-di(lower)alkenylbenzene (e.g. 1,3,5-trimethyl-1,2,6-divinylbenzene, 1,3-dimethyl-2-ethyl-4-vinyl-6-allylbenzene), tri(lower)alkenylbenzene (e.g. 1,3,5-trivinylbenzene, 1,3-divinyl-5-allylbenzene), lower alkyl-tri(lower)alkenylbenzene (e.g. 1-methyl-2,4,6-trivinylbenzene, 1-ethyl-2,4,6-triallylbenzene), di(lower)alkyl-tri(lower)alkenylbenzene (e.g. 1,3-dimethyl-2,4,6-trivinylbenzene, 1,3-diethyl-2,4,6-triallylbenzene), tri(lower)alkyl-tri(lower)alkenylbenzene (e.g. 1,3,5-trimethyl-2,4,6-trivinylbenzene, 1,3-dimethyl-5-ethyl-2,4,6-trivinylbenzene), diphenyl(lower)alkene (e.g. stilbene, 1-phenyl-2-benzylethylene), phenyl-lower alkylphenyl(lower)alkene (e.g. 1-phenyl-2-(4-methylphenyl)ethylene, 1-phenyl-2-(4-ethylphenylmethyl)ethylene), phenyl-di(lower)alkylphenyl(lower)alkene (e.g. 1-phenyl-2-(2,4-dimethylphenyl)ethylene, 1-phenyl-2-(2-methyl-4-ethylphenylmethyl)ethylene),

phenyl-tri(lower)alkylphenyl(lower)alkene (e.g. 1-phenyl-2-(2,4,6-trimethylphenyl)ethylene, 1-phenyl-2-(2,4,6-trimethylphenylmethyl)ethylene), lower alkylphenyl-lower alkylphenyl(lower)alkene (e.g. 1-(4-methylphenyl)-2-(4-methylphenyl)ethylene, 1-(2-methylphenyl)-2-(4-methylphenylmethyl)ethylene), lower alkylphenyl-di(lower)alkylphenyl(lower)alkene (e.g. 1-(4-methylphenyl)-2-(2,4-dimethylphenyl)ethylene, 1-(2-ethylphenyl)-2-(2-methyl-4-ethylphenyl)ethylene, lower alkylphenyl-tri(lower)alkylphenyl(lower)alkene (e.g. 1-(2-methylphenyl)-2-(2,4,6-trimethylphenyl)ethylene, 1-(3-ethylphenyl)-2-(2,4,6-trimethylphenylmethyl)ethylene), di(lower)alkylphenyl-di(lower)alkylphenyl(lower)alkene (e.g. 1-(2,4-dimethylphenyl)-2-(3,5-dimethylphenyl)ethylene, 1-(2,4-dimethylphenyl)-2-(2,4-dimethylphenylmethyl)ethylene), di(lower)alkylphenyl-tri(lower)alkylphenyl(lower)alkene (e.g. 1-(2,4-dimethylphenyl)-2-(2,4,6-trimethylphenyl)ethylene, 1-(2,4-dimethylphenyl)-2-[2-(2,4,6-trimethylphenyl)ethyl]ethylene), tri(lower)alkylphenyl-tri(lower)alkylphenyl(lower)alkene (e.g. 1-(2,4,6-trimethylphenyl)-2-[2-(2,4,6-trimethylphenyl)ethyl]ethylene), lower alkenylnaphthalene (e.g. 1-vinylnaphthalene, 2-vinylnaphthalene), lower alkyl-lower alkenylnaphthalene (e.g. 2-methyl-1-vinylnaphthalene, 1-methyl-2-vinylnaphthalene), di(lower)alkenylnaphthalene (e.g. 2,3-dimethyl-1-vinylnaphthalene, 2-methyl-4-ethyl-1-vinylnaphthalene), tri(lower)alkyl-lower alkenylnaphthalene (e.g. 2,3,4-trimethyl-1-vinylnaphthalene, 2,3,6-trimethyl-1-vinylnaphthalene), di(lower)alkenylnaphthalene (e.g. 1,2-divinylnaphthalene, 1-vinyl-3-allylnaphthalene), lower alkyl-di(lower)alkenylnaphthalene (e.g. 4-methyl-1,2-divinylnaphthalene, 4-methyl-1-vinyl-3-allylnaphthalene), di(lower)alkyl-di(lower)alkenylnaphthalene (e.g. 3,4-dimethyl-1,2-divinylnaphthalene), tri(lower)alkyl-di(lower)alkenylnaphthalene (e.g. 3,4,6-trimethyl-1,2-divinylnaphthalene, 3,4,6-trimethyl-1-vinyl-2-allylnaphthalene), tri(lower)alkenylnaphthalene (e.g. 1,2,3-trivinylnaphthalene, 1,2-divinyl-4-allylnaphthalene), lower alkyl-tri(lower)alkenylnaphthalene (e.g. 5-methyl-1,2,3-trivinylnaphthalene, 5-methyl-1,2-divinyl-4-allylnaphthalene), di(lower)alkyl-tri(lower)alkenylnaphthalene (e.g. 5,6-dimethyl-1,2,3-trivinylnaphthalene, 5,6-dimethyl-1,2-divinyl-4-allylnaphthalene), tri(lower)alkyl-tri(lower)alkenylnaphthalene (e.g. 5,6,7-trimethyl-1,2,4-trivinylnaphthalene, 5,6-dimethyl-7-ethyl-1,2,4-trivinylnaphthalene), etc.

As well known, these aromatic hydrocarbons are useful as the starting monomers in the production of polymers such as plastics.

The oxidative dehydrogenation method of this invention is highly excellent in the conversion rate and selectivity so that the aromatic hydrocarbon having an ethylenically unsaturated bond in a side chain can be produced in an outstanding yield by single pass. Further, palladium oxyhydrate used as the essential component of the cata-

lyst in this invention is sufficiently active even at a relatively low temperature, and the oxidative dehydrogenation can be accomplished avoiding unfavorable side reactions such as cracking, polymerization and combustion. The industrial and economical production of aromatic hydrocarbons having an unsaturated bond in a side chain is thus realized by the present invention.

Although the oxidative dehydrogenation method of this invention is generally applicable to non-aromatic cyclic hydrocarbons having at least one unsaturated bond in a side chain, there are employed as the starting material ordinarily those being not more than 2,000, preferably not more than 300 in molecular weight.

Practical and presently preferred embodiments of the present invention are shown in the following examples.

EXAMPLE 1

To a solution of 0.18 g. of palladium chloride in a mixture of 1 ml. of 0.5 N hydrochloric acid and 40 ml. of water, there are added 1 g. of asbestos and 0.5 N sodium hydroxide solution in an amount correctly equivalent to the chloride amount in the above solution. The resulting mixture is refluxed for 10 minutes. The precipitate is collected by filtration, washed and dried to give the catalyst.

A hard glass tube, 7 mm. in diameter, is packed with 0.36 g. of the catalyst above prepared. A gaseous mixture consisting of 1 part by weight of 4-vinylcyclohexene-1 and 3 parts by weight of oxygen is passed through the catalyst layer at a liquid hourly space velocity of 0.4 hr.⁻¹ at a reaction temperature of 160° C. under an autogenous pressure. The conversion rate of 4-vinylcyclohexene-1 in a single pass is 86.8%. The product consists of 91.3% by weight (selectivity) of styrene and 8.7% by weight of by-products. The total yield of styrene is 79.3%, based on the feed material.

For comparison, the reaction is carried out in the same manner as above but using as the catalyst a mixture of 1.0 g. of glass powder of 20 to 32 mesh and 100 g. of palladium-black prepared by the Willstätter method and setting the reaction temperature at 146 to 147° C. The conversion rate of 4-vinylcyclohexene-1 in a single pass is 13%. The product consists of 96% by weight of styrene and 4% by weight of by-products. The total yield of styrene is 12.5%, based on the feed material.

EXAMPLE 2

The reaction is effected as in Example 1 but using 4-isopropenylcyclohexene-1 in place of 4-vinylcyclohexene-1 as the feed material. The conversion rate of 4-isopropenylcyclohexene-1 in a single pass is 81%. The product consists of 92% by weight of α -methylstyrene and 8% by weight of by-products. The total yield of α -methylstyrene is 74.5%, based on the feed material.

EXAMPLES 3-10

The reaction is effected as in Example 1 but using a variety of feed materials. The results are set forth in the following table:

Feed material	Reaction temperature, °C.	Main product	Conversion rate, percent	Selectivity, percent
Example:				
3..... Vinylcyclohexane	160	Styrene.....	72	87
4..... 1-vinylcyclohexadiene-1,3.....	160	do.....	89	92
5..... 1,2-divinylcyclohexene-3.....	160	1,2-divinylbenzene.....	87	81
6..... 3-cyclohexyl-2-methyl-propene-1.....	160	3-phenyl-2-methyl-propene-1.....	69	90
7..... 5-(3-cyclohexenyl)-pentene-1.....	160	5-phenylpentene-1.....	82	89
8..... 1-cyclohexylcyclohexene-1.....	220	1-phenylcyclohexene-1.....	100	72
9..... 2-vinyl-1,2-dihydronaphthalene.....	190	2-vinyl-naphthalene.....	98	73
10..... 1-phenyl-2-cyclohexylethylene.....	240	Stilbene.....	100	69

What is claimed is:

1. A method for the oxidative dehydrogenation of a non-aromatic cyclic hydrocarbon having at least one unsaturated bond in a side chain which comprises contacting

the non-aromatic cyclic hydrocarbon in the presence of oxygen with a catalyst consisting essentially of palladium oxyhydrate to give the corresponding aromatic hydrocarbon retaining the said unsaturated bond.

2. The method according to claim 1, wherein the non-aromatic cyclic hydrocarbon is the one selected from the group consisting of the compounds of the formula:

wherein X is a substituted or unsubstituted monocyclic or bicyclic non-aromatic hydrocarbon group, R₁, R₂ and R₃ are each a hydrogen atom, a lower alkyl group, a cyclohexyl group, a lower alkylcyclohexyl group, a di(lower)alkylcyclohexyl group, a tri(lower)alkylcyclohexyl group, a cyclohexyl(lower)alkyl group, a lower alkylcyclohexyl(lower)alkyl group, a di(lower)alkylcyclohexyl(lower)alkyl group, a tri(lower)alkylcyclohexyl group, a cyclohexenyl group, a lower alkylcyclohexenyl group, a di(lower)alkylcyclohexenyl group, a tri(lower)alkylcyclohexenyl group, a lower alkylcyclohexenyl(lower)alkyl group, a di(lower)alkylcyclohexenyl(lower)alkyl group, a tri(lower)alkylcyclohexenyl group, a cyclohexenyl(lower)alkyl group, a lower alkylcyclohexenyl(lower)alkyl group, a di(lower)alkylcyclohexenyl(lower)alkyl group, a tri(lower)alkylcyclohexenyl group, a cyclohexadienyl group, a lower alkylcyclohexadienyl group, a di(lower)alkylcyclohexadienyl group, a tri(lower)alkylcyclohexadienyl group, a cyclohexadienyl(lower)alkyl group, a lower alkylcyclohexadienyl(lower)alkyl group, a di(lower)alkylcyclohexadienyl(lower)alkyl group, a tri(lower)alkylcyclohexadienyl(lower)alkyl group, an aryl group or an ar(lower)alkyl group and m is an integer from 1 to 3 and the compounds of the formula:

wherein Y is a lower alkylene group and X, R₁, R₂, R₃ and m are each defined above.

3. The method according to claim 1, wherein the non-aromatic cyclic hydrocarbon is a lower alkenylcyclohexane.

4. The method according to claim 1, wherein the non-aromatic cyclic hydrocarbon is a lower alkenylcyclohexene.

5. The method according to claim 1, wherein the non-aromatic cyclic hydrocarbon is a lower alkenylcyclohexadiene.

6. The method according to claim 1, wherein the dehydrogenation is carried out at a temperature from about 50 to about 350° C.

7. The method according to claim 1, wherein the molar ratio of oxygen to the non-aromatic cyclic hydrocarbon is from 0.1:1.0 to 10:1.0.

8. The method according to claim 1, wherein the cat-

alyst consists of palladium oxyhydrate and asbestos.

9. In the selective dehydrogenation of a non-aromatic cyclic hydrocarbon selected from the group consisting of lower alkenylcyclohexane, lower alkenylcyclohexene and

lower alkenylcyclohexadiene to the corresponding lower alkenylbenzene, a method which comprises contacting the non-aromatic cyclic hydrocarbon in the presence of oxygen with a catalyst consisting essentially of palladium oxyhydrate at a temperature from about 50 to about 350° C. under an autogenous pressure, the molar ratio of oxygen to the non-aromatic cyclic hydrocarbon being from 0.1:1.0 to 10:1.0.
